Primary Examiner—Susan Bennett Hattan

(57) **CLAIM**

The ornamental design for a dispensing pump head, as shown and described.

DESCRIPTION

FIG. 1 is a front perspective view of a dispensing pump head; FIG. 2 is a front elevation view thereof; the broken line showing of elements behind the trigger and inside the shroud depicting environmental subject matter only and forming no part of the claimed design; FIG. 3 is an elevation view of the rear thereof; FIG. 4 is an elevation view of the right side thereof; FIG. 5 is an elevation view of the left side thereof; FIG. 6 is a plan view of the top thereof; and, FIG. 7 is a bottom plan view thereof, the broken line defining boundary of the claimed design and forming no part thereof.
